UNITED STATES PATENT OFFICE.

FRED C. IELFIELD, OF SILVER CREEK, NEW YORK, ASSIGNOR TO COLUMBIA POSTAL SUPPLY COMPANY, OF SILVER CREEK, NEW YORK, A CORPORATION OF NEW YORK.

MAIL-MARKING MACHINE.

No. 828,808.

Specification of Letters Patent. Patented May 26, 1908.

Application filed January 12, 1907. Serial No. 351,908.

To all whom it may concern:

Be it known that I, FRED C. IELFIELD, a citizen of the United States, residing at Silver Creek, in the county of Chautauqua and State of New York, have invented a new and useful Improvement in Mail-Marking Machines, of which the following is a specification.

This invention relates to a mail marking machine whereby letters and similar pieces of mail matter are post marked and canceled and more particularly to a machine of this character in which the printing and impression rollers are held apart when no letter is in the proper position to be fed between the same but are permitted to bear against opposite sides of a letter which is properly fed between them for canceling the same.

The object of this invention is to produce an improved machine of this type of simple, reliable and durable construction whereby letters &c., may be canceled or marked expeditiously and without undue wear and noise and without soiling the mail matter.

In the accompanying drawings consisting of 3 sheets: Figure 1 is a fragmentary vertical section of the machine taken substantially in line 1—1, Fig. 3. Fig. 2 is a detached elevation of the rock arm or carrier which supports the impression roller and other parts. Fig. 3 is a sectional top plan view of the machine taken in line 3—3, Fig. 1. Fig. 4 is a fragmentary sectional top plan view similar to Fig. 3, showing the impression roller in a different position. Fig. 5 is a horizontal section taken below the table in line 5—5, Fig. 1. Fig. 6 is a fragmentary plan view showing a modification of my invention.

Similar letters of reference indicate corresponding parts throughout the several views.

A represents the horizontal table of the machine which is supported upon a pedestal or other support. Upon the front part or feed end *a* of this table are placed the pile of letters or pieces of mail matter which are to be canceled or post marked and upon the rear part or delivery end *a'* thereof these letters or pieces are again stacked after being canceled or marked.

B represents a longitudinal upright wall arranged upon the table and forming the front sides of the receiving and delivery spaces or compartments of the table. Be-

tween the feed and delivery ends of the table 55 an upright wall or partition C is arranged substantially at right angles or transversely to the front wall and separated from the latter by a passage way which is yieldingly closed by means of an elastic oblique gate or tongue *c* 60 which is secured at its front end to said partition and bears at its rear end against the front wall. Opposite the feed or receiving end of the table the front wall is provided with a suction opening *d* which communicates with 65 the front end of a suction head D arranged on top of the table, said head being in turn connected by a conduit *e* with a fan or other air exhausting device, whereby the foremost letters of the pile on the feed end of the table 70 are caused to be successively drawn pneumatically against the side of the front part of the wall B. Each letter after being thus drawn against the front wall is moved forwardly lengthwise thereof by means of a separator or feeder which preferably consists of an oblong head or cam F arranged in the suction head and secured to the upper end of an upright shaft *f* and provided on its edge or periphery with a facing of rubber or similar 80 material. During each rotation of the separator its salient part sweeps rearwardly beyond the face of the front wall and by engaging the letter sucked against the same the letter is moved forwardly and away from the 85 pile on the feed end of the table. During its forward movement the letter or piece of mail matter deflects the elastic gate *c* and passes rearwardly through the passage way between the partition C and the front wall B. 90

G, H represent the cooperating printing roller or wheel and impression roller or platen which are arranged on opposite sides of the path of the letter on its way from the feed end to the delivery end of the table, whereby 95 said letter is canceled or post marked while thus passing between said rollers. The printing roller is arranged on the left side of the path of the letter and is mounted upon the upper end of a vertical shaft *g* which may 100 be driven in any suitable manner. On the upper part of its periphery, the printing roller is provided with any suitable canceling die *l* designed to cancel or post mark a letter with a date or canceling lines or both, said 105 die being coated with ink by means of an ink roller *j* arranged to engage the die.

The impression roller only approaches the

printing roller when a letter is properly presented to the same, being at all other times separated or moved away from the printing roller, so that the impression roller will not become coated with ink from the die on the printing roller, thus avoiding smearing or soiling of the letters passing between these rollers.

11 k, k' represent the upper and lower sections of a divided upright shaft which are connected at their opposing ends by a coupling k^2 constructed to permit these shaft sections to be deflected laterally relatively to each other but compelling them to turn together. The 15 upper shaft section k projects through a transverse slot in the table and is provided immediately above the impression roller with a feed disk or flange M which is adapted to engage its periphery with a segmental feed 20 disk, rim or flange m on the shaft g below the printing roller.

25 The lower section k' of the impression roller shaft is mounted in a swiveling step bearing N so as to be capable of tilting 30 therein and is operatively connected with the shaft g of the printing roller by a gear wheel n and pinion n' which are preferably constructed to produce two rotations of the impression roller shaft to one of the printing 35 roller.

35 O represents a horizontal rocking arm or carrier which is pivoted at one end to the underside of the table and provided at its opposite end with a bearing in which the upper section k of the impression roller shaft is journaled. The movement of this arm O in the direction for carrying the impression roller toward the printing roller is limited by a stop o^1 against which it is yieldingly held by 40 a spring o^2 . This stop is preferably arranged on a horizontally adjustable arm o^3 , as shown in Fig. 5, to permit adjusting the position of this impression roller shaft relatively to the printing roller shaft.

45 The preferred means for adjusting the arm O consists in pivoting the same at one end by a vertical pin o^4 to the table while its opposite free end is connected by a bolt-and-slot connection o^5, o^6 with the table, as shown in 50 the last mentioned figure.

55 The impression roller has a hub h of metal which rests loosely on the top of the disk M and a periphery h' of rubber or other elastic material which is adapted to receive the pressure of the printing wheel. As shown in Fig. 1 of the drawings, the impression roller is compelled to turn with the disk M and the shaft k, k' but is free to move laterally relatively thereto by means of a pin p arranged 60 on the underside of the hub of the impression roller and projecting into an opening p^1 in the disk M . If desired, this pin and opening connection between these parts may be omitted in which case the impression roller is driven 65 solely by frictional contact with the disk M .

and the letters passing between the same and the printing roller.

The mechanism whereby the impression roller is moved laterally into and out of its operative position relative to the printing 70 wheel is constructed as follows:—

75 Q represents an eccentric which is pivoted on the shaft section k above the feed disk M and upon the periphery of which the hub of the impression roller is pivoted. As shown in Figs. 3 and 4, the salient part of this eccentric projects forwardly or in the direction in which the letters move from the receiving 80 to the delivery side of the table. At its upper end the eccentric is provided with a rearwardly projecting tappet q which overhangs the impression roller. The latter together with the eccentric are held against upward movement on the shaft section k by a washer q^1 secured by a screw to the upper end of 85 said shaft section and engaging with the upper side of the tappet.

90 R represents a shifting arm and S a trigger which are arranged above the table in rear of the impression roller and which are caused to 95 rotate horizontally in unison by forming both of them on or securing them to the same hub r . The latter is pivoted on the upper end of a vertical pin s which projects upwardly from the rocking carrier through a slot r^1 in 100 the table. The shifting arm projects forwardly from the pivot pin s and normally engages at its front end against the inner side of said tappet while the trigger normally projects from the pivot pin s obliquely forward across the path of the letters and terminates close to the periphery of the printing wheel. The movement of the shifting arm and trigger toward the letter path is limited by a stop t which is adapted to be engaged by 105 the shifting arm. The shifting arm and trigger are yieldingly held in this inner position by a spring t^1 connected at one end with the rear side of the hub r while its opposite end is connected with a bracket u projecting laterally from the collar u^1 which is secured to the pin s and carries the stop t . The trigger is preferably constructed in the form of a two prong fork and is arranged higher than the top of the printing wheel. 110

115 V represents a feeling or trip finger which is arranged on the upper side of the printing wheel with its free end opposite the space between the prongs of said forked trigger and adapted to coöperate with the trigger for 120 shifting the impression roller into its operative position.

When no letter is fed forward against the trigger, the same projects across the path thereof, as shown in Fig. 4, and at such time 125 the trip finger passes idly through the forked trigger during each rotation without actuating the latter. When the letter is fed out of time with the printing mechanism, the same is arrested in its forward movement by 130

engagement of its front edge with the rear side of the trigger, as shown by dotted lines in Fig. 4, the spring t^4 being sufficiently strong to prevent movement of the trigger by the letter.

A letter is out of time when the same reaches the trigger after the front part of the die has passed the printing line. If the letter at this point were permitted to pass forwardly between the impression roller and die only the rear part of the latter would print on the letter and thus cancel the same imperfectly and possibly miss some of the postage and fail to affix the canceling date on the letter. A letter is in time when it engages the trigger before the front end of the die passes the printing line in which case the letter is permitted to move forwardly between the impression roller and die and receive the entire imprint of the latter, so that all of the postage stamps which are ordinarily affixed to letters are canceled and the date is affixed thereto in its entirety.

While the trigger is in the position shown in Fig. 4, the forward rotation of the impression roller by frictional contact with the eccentric causes the latter to be also turned in the same direction until the tappet engages with the outer side of the shifting arm, thereby causing the eccentric to move the impression roller away from the printing wheel and prevent the inked type on the periphery of the latter from smutting the impression roller.

The trip finger is mounted on the printing wheel slightly in advance of the front end of the die and feed flange thereon. When a letter engages properly at its front end with the trigger so as to bridge the gap between its prongs or tines, the trip finger engages with the letter and pushes the same together with the trigger laterally toward the impression roller and immediately thereafter the lower part of the letter is grasped between the feed disks or flanges of the printing wheel and impression roller shafts and shot forward. At the same time, the shifting arm by engaging with the tappet turns the eccentric in a direction opposite to that in which the impression roller normally rotates, thereby moving the impression roller bodily toward the printing wheel and causing the die of the latter which at this time is in the printing position to produce a post mark on the letter during the forward movement of the same. The impression roller remains in this position during the entire passage of the letter. While the impression roller is out of action or in its retracted position, the shifting arm is more nearly parallel with the face of the tappet and the latter is engaged near its base or pivot by the outer free end of the shifting arm, as shown in Fig. 4. But when the impression roller

is in action or in its operative position the shifting arm is arranged at right angles to the face of the tappet and engages its outer end farther from its base or pivot, as shown in Fig. 3, thereby positively locking the impression roller in its working position and preventing the same from being deflected by the lateral pressure of a letter into an inoperative position so long as a piece of mail matter is passing between the printing wheel and impression roller. When the rear end of the letter clears the trigger, the latter is immediately projected across the letter path by the spring t^4 in position to intercept the next letter. As the trigger and shifting arm resume their former position, the forward rotation of the impression roller causes the eccentric to be turned outwardly or away from the letter path, thereby carrying the impression roller bodily in the same direction and preventing engagement of its periphery with the inked die of the printing wheel during any idle rotary movement thereof, whereby the backs of subsequent letters are prevented from becoming soiled or smutted. The rate of movement at the periphery of the printing wheel and impression roller and their feed disks is the same, the gearing between the shafts of these parts being suitably proportioned to obtain this result.

If desired, the impression roller H^1 may be mounted concentrically on the shaft g and the printing wheel G^1 may be mounted on the eccentric and moved bodily toward and from the impression roller, this being a modification of my invention and shown in Fig. 6.

While canceling or marking letters of ordinary thickness, the carrier O does not change its position and remains in engagement with the stop o^1 , but when a letter or piece of mail matter of unusual thickness enters between the printing wheel and impression roller, the carrier together with the parts mounted thereon are deflected the required extent, this movement being resisted by the spring o^2 which again returns the parts to their normal position.

As the letters issue from the impression roller and printing wheel they stand in front of a rotary packer W which is mounted on the upper end of a shaft w and sweeps through an opening in the rear part of the front wall B for successively stacking the letters on the delivery end of the table. Motion is transmitted from the shaft of the printing wheel to the separator shaft by gear wheels x , x^1 and x^2 and to the packer shaft by gear wheels x , y and z , as shown in Fig. 5.

I claim as my invention:

1. A mail marking machine comprising a printing member or wheel, an impression member or wheel, an eccentric on which one of said members is pivoted, a trigger held yieldingly in the letter path, means for mov-

- ing the trigger out of the letter path, and means for transmitting the movement of the trigger to said eccentric for carrying the member mounted thereon toward the other member, substantially as set forth.
2. A mail marking machine comprising a printing member or wheel, an impression member or wheel, an eccentric on which one of said members is pivoted, a trigger held yieldingly in the letter path, means for moving the trigger out of the letter path, and means for transmitting the movement of the trigger to said eccentric for carrying the member mounted thereon toward the other member consisting of a tappet arranged on said eccentric and a shifting arm connected with the trigger and engaging with said tappet, substantially as set forth.
3. A mail marking machine comprising a printing wheel, an impression roller, an eccentric on which the impression roller is pivoted, a tappet arranged on the eccentric, a shifting arm engaging with the tappet, a trigger connected with the shifting arm, a spring for yieldingly projecting the trigger across the letter path, and a trip finger rotating with the printing wheel and adapted to engage with a letter resting against the trigger and move the latter out of said path, substantially as set forth.
4. A mail marking machine comprising a printing wheel, an impression roller, an eccentric on which the impression roller is pivoted, a tappet arranged on the eccentric, a shifting arm engaging with the tappet, a trigger connected with the shifting arm and having the form of a fork, a spring connected with said shifting arm and trigger and operating to hold the tines of the trigger yieldingly across the letter path, and a trip finger mounted on the printing wheel and adapted to either pass between the tines of the trigger or to turn the same by engaging a letter resting against the same, substantially as set forth.
5. A mail marking machine comprising a printing wheel, an impression roller, an eccentric on which said impression roller is pivoted and whereby the letter is moved laterally toward and from the printing wheel, a tappet arranged at the upper end of the eccentric, a shifting arm engaging said tappet, a trigger connected with the shifting arm, a spring connected with the hub of said shifting arm and trigger and operating to yieldingly hold the trigger across the letter path and the shifting arm in its inoperative position, and a trip finger arranged on the printing wheel and coöperating with said trigger and a stop for limiting the movement of the trigger and shifting arm under the action of said spring, substantially as set forth.
6. A mail marking machine comprising a printing wheel, a feed disk arranged below said wheel and turning therewith, an impression roller movable toward and from the printing wheel, a feed disk frictionally supporting the impression roller on its underside and coöperating with the feed disk below the printing wheel, an eccentric having the impression roller turning about its periphery and pivoted on the same axis as the feed disk below the impression roller, a tappet arranged on the eccentric, a trigger connected with the shifting arm and adapted to project across the letter path, and a trip finger connected with the printing wheel and coöperating with said trigger, substantially as set forth.
7. A mail marking machine comprising a printing wheel, a feed disk arranged below said wheel and turning therewith, an impression roller movable toward and from the printing wheel, a feed disk frictionally supporting the impression roller on its underside and coöperating with the feed disk below the printing wheel, a pin, arranged on said impression roller and engaging with an opening in the feed disk below the same, substantially as set forth.
8. A mail marking machine comprising a printing wheel, a feed disk arranged below the printing wheel, a carrier movable laterally relatively to the printing wheel, a shaft journaled on said carrier, a feed disk secured to said shaft and adapted to coöperate with the feed disk below the printing wheel, an eccentric journaled on said shaft, an impression roller journaled on said eccentric and adapted to coöperate with the printing wheel, a tappet arranged on said eccentric, a hub pivoted on the carrier and provided with a shifting arm engaging with said tappet and with a trigger adapted to project across the letter path, a spring operating to turn the shifting arm and trigger in the direction in which the trigger crosses the letter path and the shifting arm is retracted, and a trip finger mounted on the printing wheel and adapted to shift said trigger out of said letter path and causing the eccentric to move the impression roller toward the printing wheel, substantially as set forth.

Witness my hand this 9th day of January, 1907.
